UNITED STATES PATENT OFFICE.

JOSEPH H. KING, OF SAN DIEGO, CALIFORNIA.

GRINDSTONE.

Application filed March 3, 1923. Serial No. 622,536.

To all whom it may concern:

Be it known that I, JOSEPH H. KING, a citizen of the United States, residing at San Diego, in the county of San Diego and State of California, have invented a certain new and useful Grindstone, of which the following is a specification.

My invention relates to grindstones, more particularly to that class of grindstones in which a portion of the grinding member is adapted to be positioned in water or other liquid while in operation.

It has been customary in the past to provide a grindstone with troughs or pans partly filled with water in which the stone stood at all times until the water was used or emptied out. By this means the portion of the grindstone standing in the water was subjected to disintegration and softened so that when the stone was used for grinding the portion thus disintegrated or softened would wear down more quickly, making the grinding surface eccentric and very irregular, and useless for fine work.

The objects of this invention are: First, to provide a grindstone of this class in which a trough, partly filled with water or other liquid, is movably positioned at the lower portion of the stone so that when the grindstone is not in use the trough may be lowered, and when in use the trough may be raised and the stone be positioned in the water; second, to provide a grindstone of this class in which the trough will be automatically positioned so that the liquid in the trough will surround a portion of the stone when the same is in use; third, to provide an apparatus of this class for grindstones which can be very easily adjusted to accommodate different sizes of grindstones and for positioning the stone in the liquid at different depths; fourth, to provide a novelly constructed and operated apparatus of this class, and fifth, to provide an apparatus of this class which is very simple and economical of construction, durable, practical, which may be easily installed on any grindstone, and which will not readily deteriorate or get out of order.

With these and other objects in view, as will appear hereinafter, my invention consists of certain novel features of construction, combination and arrangement of parts

and portions as will be hereinafter described in detail and particularly set forth in the appended claims, reference being had to the accompanying drawings and to the characters of reference thereon, which form a part of this application, in which:

Figure 1 is a side elevational view of my grindstone, showing certain hidden parts by dotted lines and showing by other dotted lines the upwardly shifted position of the trough and other correspondingly shifted parts; Fig. 2 is a plan view thereof; Fig. 3 is a fragmentary, rear elevational view thereof, showing certain parts and portions broken away to facilitate the illustration, and Fig. 4 is an enlarged, detailed view of the pivotal joint connecting means between the operating arm and the trough support.

Like characters of reference refer to similar parts and portions throughout the several views of the drawings.

The supporting frame 1, grindstone member 2, journal members 3, treadle members 4, connecting rods 5, crank members 6, trough 7, trough supporting member 8, operating arms 9, pins 10, bolt 11, seat supports 12, rivets 13, seat member 14, bolts 15 and 16 and the guard member 17, constitute the principal parts and portions of my grindstone structure.

The supporting frame 1 of my grindstone structure consists of two front legs 1^a and a rear leg 1^b, connected at their upper ends by the spaced apart beam members 1^c, secured together in such position and to the outer edges of the leg members, the front legs being reinforced therewith by the braces 1^d. The circular grinding member 2 is positioned between the spaced beam members 1^c and is revolubly mounted in the journal members 3, positioned and secured to the upper sides of the beam members. The grindstone member 2 is rotated by means of the treadle members 4 pivotally mounted at their front ends on the front legs 1^a and connected at their middle portions to the crank members 6 by means of the connecting rods 5, said crank members being secured to the ends of the shaft of the grindstone member.

My trough apparatus consists of a segment-shaped trough 7 around the middle portion of which extends the U-shaped

trough-supporting member 8 with its leg portions extending upwardly, to the upper ends of which are pivotally connected the operating arms 9 by means of the removable pins 10 secured in place by the cotter pins 10^a, said operating arms 9 being pivotally mounted intermediate their ends on the beam members of the supporting frame by the bolts 11. At the outer ends of said 10 operating arms are secured the J-shaped seat supporting members 12 which support the seat 14, substantially as shown in the drawings. It will be noted that the ends of the operating arms 9, connected to the 15 U-shaped, trough supporting member 8, are turned inwardly and backwardly to receive the upper ends of the member 8 for supporting the same in alignment therewith and for loosely supporting the same there- 20 in to permit free pivotal movement of the member 8, said member 8 being provided at its upper ends with a plurality of holes 8^a for adjustably connecting said member with the operating arms 9. It will also be noted 25 that the portions of the operating arms 9 forward of their pivotal mounting are separated sufficiently to straddle the stone 2 and immediately behind their pivotal mounting are offset inwardly and extend backwardly 30 through a slot 1^c in the upper portion of the rear leg 1^b of the supporting frame. To the extreme rear end of the arms 9 are secured the shorter legs of the J-shaped seat supporting members 12 by the rivets 13, the 35 longer legs of which seat supporting members are extended outwardly and downwardly straddling the beams 1^c of the supporting frame and are secured together near their lower ends by the bolt 16, which serves as a stop for the upper position of the seat or the lower position of the trough, this position being regulated by the position of the bolt 16 which is adapted to be inserted in the different holes 12^a in the longer legs of 40 said J-shaped seat supporting members. The connecting portion of the long and short legs of said J-shaped members 12 serve as a stop for the lower position of the seat and the upper position of the trough, 45 and also the securing portion of the seat 14, which is secured thereto by the bolts 15. The conventional, channel-shaped guard 17 is provided at the rear portion of the grind- 50 stone member 2 for the support of the tools and protection against splashing of water. Though I have shown and described a particular construction, combination and arrangement of parts and portions, I do not 55 wish to be limited to this particular construction, combination and arrangement, but desire to include in the scope of my invention, the construction, combination and arrangement substantially as set forth in the appended claims.

60 It is obvious from this construction that

there is provided a grindstone apparatus in which the trough for wetting the grindstone member therein is movably mounted at the lower portion of said grindstone member; that the trough is automatically shifted in an upward position for wetting the grindstone member in the liquid provided therein when the operator is ready and in a position to use the grinding apparatus, and in which the trough will automatically be lowered when not using the grindstone; that there is provided a grindstone of this class in which the trough is shifted upwardly and downwardly, respectively, by the operator sitting on the seat 65 provided on the frame thereof when using the grindstone, and by removing himself therefrom when through; that there is provided a novelly constructed apparatus of this class for shifting the trough of grindstones, and that there is provided a grindstone apparatus of this class which is very simple and economical of construction, durable, efficient, applicable for different styles and sizes of grindstones, and which will not 70 readily deteriorate or get out of order.

Having thus described my invention, what I claim as new and desire to secure by Letters Patent, is:

1. An apparatus of the class described including a supporting frame, a grinding member revolvably mounted thereon, a manual means for revolving said grinding member, a trough for said grinding member, vertically shiftably positioned at the lower 90 portion of the grinding member, a lever pivotally mounted on said supporting frame, to the one end of which is pivotally connected the trough and a seat member supported at the opposite end of said lever, upon which 95 the operator sits for manually revolving said grinding member and for vertically shifting said trough when the operator gets off of said seat.

2. An apparatus of the class described including a supporting frame, a grinding member revolvably mounted thereon, a manual means for revolving said grinding member, a trough for said grinding member, vertically shiftably positioned at the lower 100 portion of the grinding member, lever means mounted on said supporting frame for raising and lowering said trough, and a seat supported by said lever means for the operator of said apparatus, whereby the trough 105 is automatically shifted upwardly or downwardly by the movement of said seat, when the operator gets on and off of said seat.

3. An apparatus of the class described including a supporting frame, a grindstone member revolvably mounted thereon, a means for revolving said grindstone member, a trough adapted to be partly filled with a liquid, positioned at the lower portion of said grindstone member and shift- 110 115 120 125 130

able vertically therewith, a lever pivotally mounted on said supporting frame, to the one end of which is pivotally connected the trough, a stop means provided on said lever for limiting the movement of said trough, and a seat member supported at the opposite end of said lever for vertically shifting said

trough, when the operator gets on and off of said seat.

In testimony whereof, I have hereunto ¹⁰ set my hand at San Diego, California, this 26th day of February, 1923.

JOSEPH H. KING.
